BERTRAM J. GANS, OF NAPA, CALIFORNIA, ASSIGNOR TO CAMERON AND COMPANY INCORPORATED, OF NAPA, CALIFORNIA, A CORPORATION OF CALIFORNIA.

BUTTON-SEWING-MACHINE ATTACHMENT.

1,062,328.

Specification of Letters Patent.

Patented May 20, 1913.

Application filed April 8, 1912. Serial No. 689,110.

To all whom it may concern:

Be it known that I, BERTRAM J. GANS, a citizen of the United States, residing at Napa, in the county of Napa and State of California, have invented new and useful Improvements in Button-Sewing-Machine Attachments, of which the following is a specification.

This invention relates to attachments for sewing machines and particularly to an attachment for use on button sewing machines for holding a reinforcing fabric in position beneath the cloth on which a button is being sewed to the cloth.

15 The invention consists of the parts and the construction and combination of parts as hereinafter more fully described and claimed, having reference to the accompanying drawings, in which—

20 Figure 1 is a perspective view of a portion of a sewing machine with the device applied. Fig. 2 is a perspective view of the device removed from the machine. Fig. 3 is a cross section through the throat plate of 25 the machine with the device in section thereon.

For the purpose of reinforcing fine fabric or cloth, upon which buttons are sewed, it is desirable to apply and attach to the opposite 30 side of the cloth from the button a small reinforcing disk or piece 2, Fig. 3.

The purpose of the present invention is to provide a simple attachment for sewing machines, especially button sewing machines; 35 the purpose of the attachment being to retain the small reinforcing piece in position beneath the cloth on which the button is being sewed.

In carrying out this invention I employ 40 a thin steel or other metal plate A of suitable proportions, which may be screwed to the button guide 5 of a machine; the rear end of the plate A being slightly bowed, so that the screws 3, when screwed into the button 45 guide of the machine, can draw the device or plate A down with sufficient pressure to hold it steady.

Preferably the attachment or plate A is of quite thin material, approximately the thickness 50 of the fabric which is used to form the reinforcing pieces 2. There is formed in the attachment A a perforation 4, which may be round or other shape, as desired, according to the size and shape of the cloth washer

or disk 2; and into which opening one of the 55 reinforcing disks may be inserted by the operator prior to the downward feeding of the button through the button guide or clamp 5.

The perforation 4 of the receptacle or 60 plate A is arranged over the needle hole 6 of the throat plate, so that the needle 7 of the machine may reciprocate through the throat plate and sew the reinforcing disk 2 to the cloth as the button is being sewed. 65

For the purpose of preventing accidental displacement of the fabric washer or reinforcing piece 2 from the aperture 4, a transverse or tangentially arranged strip 8 is attached to the upper surface of the member 70 A. This pressure device 8 operates to hold the reinforcing disk or piece 2 in place during the sewing on a cloth of a button, which may be fed over the aperture 4 from the button clamp or guide 5. 75

After the button has been thoroughly sewed on to the goods, the latter is advanced and the reinforcing piece 2 is drawn from the aperture 4 in the receptacle A. The retaining strip 8 keeps the reinforcing fabric or 80 material from slipping out of the hole 4 when the main fabric is placed on the feed plate A to have the button sewed on.

The operation of sewing a button on a fabric with a reinforcement made of a woven 85 fabric or other material has generally been done by hand with an ordinary needle and thread. This is a slow and costly process. My invention enables the same operation to be done with a button sewing machine in a 90 strong, neat, workmanlike and expeditious manner, giving a better result at a very much reduced cost.

The essential idea of this invention is the use of a countersink or pocket or receptacle 95 however formed, in conjunction with the button holder and needle, for holding a reinforcing disk in position so that the sewing of the disk, button and fabric is done simultaneously and mechanically. 100

Having thus described my invention, what I claim and desire to secure by Letters Patent is—

1. The combination in a sewing machine, of a button holder, and a reinforcing-piece 105 holder on the same, said holder having a perforation for receiving the reinforcing piece, said holder having a portion overlying

ing a part of the perforation and under which the reinforcing piece is slipped and held.

2. The combination with a button sewing machine, having button holding means, of a detachable disk holder thereon having an aperture for the reception of a reinforcing disk, and means on the holder for temporarily restraining the reinforcing disk in said aperture.

3. The combination in a button sewing machine, of a button holding mechanism, a detachable disk holder comprising a thin

plate provided with an aperture adapted to receive a reinforcing disk and hold the same 15 in position, and a retaining plate mounted upon said detachable disk holder in such manner as to cover a portion of said aperture.

In testimony whereof I have hereunto set 20 my hand in the presence of two subscribing witnesses:

BERTRAM J. GANS
